Primary Examiner — Richard E Chilcot

(74) Attorney, Agent, or Firm — Oblon, McClelland,
 Maier & Neustadt, L.L.P.(57) **CLAIM**

The ornamental design for a ingot mold, as shown and described.

DESCRIPTION

1. Ingot molds
  - 1.1 is a bottom, front, and right side perspective view of an ingot mold;
  - 1.2 is a front elevational view thereof;
  - 1.3 is a rear elevational view thereof;
  - 1.4 is a top plan view thereof;
  - 1.5 is a bottom plan view thereof;
  - 1.6 is a left side elevational view thereof; and
  - 1.7 is a right side elevational view thereof.
- The broken lines are for illustrative purpose only and form no part of the claimed designs.
